UNITED STATES PATENT OFFICE

2,371,522

PHONOGRAPH

William H. Hutter, Chicago, Ill., assignor to Rock-Ola Manufacturing Corporation, Chicago, Ill., a corporation of Delaware

Application July 17, 1941, Serial No. 402,833

1 Claim. (Cl. 248—21)

This invention relates in general to phonographs, and more particularly to novel means for supporting and mounting the operating mechanism thereof in the usual casing or cabinet.

In a multi-record phonograph, such as that disclosed in United States Letters Patent No. 2,159,834, issued May 23, 1939, to Paul H. Smyth, Jr., the operating mechanism is enclosed in an outer casing or cabinet and usually includes means for moving a selected or desired record onto a rotatable turntable and into playing position, means for rotating the turntable, and means for playing or reproducing the record. The operation of these different mechanisms sets up vibrations which may, and at times will, build up and amplify each other to such an extent as to distort the sound reproduction and cause undesirable booming, squealing, etc., by the speaker. The same deleterious results may also be occasioned by accidental jarring of the cabinet or by otherwise causing vibrations originating exteriorly of the machine to be transmitted to the record reproducing means.

A principal object of this invention, therefore, is to eliminate, or at least to materially minimize, such undesirable results in the operation of a phonograph.

Another important object of the invention is the provision, in a phonograph having such multi-part operating mechanism, of novel means for so supporting the same in a cabinet as to damp vibrations emanating either from the mechanism or from the exterior of the machine to minimize the transmission thereof to the sound reproducing means.

A further object of the invention is to provide individual supporting means for the different parts of the operating mechanism of a phonograph, and means interconnecting the same having different periods of vibration to cause the vibrations which would normally be transmitted from one part to another to be effectively damped.

Numerous other objects and advantages of the invention will be apparent as it is better understood from the following description, which, when taken in connection with the accompanying drawings, discloses a preferred embodiment thereof.

In the drawings,

Figure 1 is a transverse vertical section of a phonograph embodying the features of the instant invention;

Fig. 2 is a front elevational view, with the cabinet and part of the mechanism removed and

the main mechanism supporting frame shown in section;

Fig. 3 is a top plan view of the operating mechanism, with the cabinet shown in section; and

Figs. 4 and 5 are detail vertical sections taken substantially on the lines 4—4 and 5—5, respectively, of Fig. 3.

Referring more particularly to the drawings, the phonograph illustrated is of the type disclosed in the previously noted Smyth Patent No. 2,159,834, and the alphabetical reference characters used herein are the same as those employed in the patent and designate identical mechanism. Since this mechanism is described in detail in said patent, a brief and general explanation thereof will be sufficient herein for a complete understanding of the present invention.

The phonograph comprises an outer casing or cabinet A of suitable construction for accommodating the operating mechanism, including record carrying and reproducing devices which cooperate to translate the irregularities of a record sound track into mechanical vibrations and to convert the latter into electrical impulses which are supplied to amplifier means not shown herein, and a speaker D for converting the amplified electrical impulses into sound. Operation of the phonograph is controlled by coin-operated means and record selector control means V, as described in detail in said patent, through the agency of which an electric motor or driving means N is energized to cause rotation of a master cam M, and a second electric motor or driving means O is also energized to rotate a turntable G. The records are carried by a plurality of ring shaped trays J arranged one above another in stack relationship, and pivotally associated with a record carrier supporting or mounting assembly I, to be swingable between their normal inoperative position of the instant drawings and an operative position above and in vertical alignment with the turntable G.

Rotation of the master cam M causes the tray J carrying the record selected for playing to be swung to its delivery position in alignment with the rotating turntable G. The master cam M then actuates a cam follower S to raise a reciprocable slide R, which carries with it an arm T engaging a shaft P which supports the turntable G at its upper end. The turntable G is thus raised from its normal or inoperative position of Fig. 2, through the selected record carrier J to remove the selected record therefrom, and to its uppermost position to present the record

in playing position for engagement by a tone arm or reproducer means H. As the turntable G reaches such playing position, the electric motor or driving means N is deenergized to stop the rotation of the master cam M.

When the tone arm or reproducer means H reaches the end of the record groove to complete playing of the record, the electric motor or driving means N is again energized to rotate the master cam M. Resumption of rotation of the cam M causes actuation of the follower S, slide R and arm T to lower the turntable G through the selected record carrier J and back to normal position. As the turntable G is lowered from playing position, reproducer return means U functions to return the reproducer means H to normal or starting position, and after the played record is deposited on its carrier J, the latter is swung back to its stack position. The circuit including the electric motor or cam driving means N and that including the electric motor or turntable rotating means O are then interrupted to complete the cycle of operations, unless more than the one record has been selected for playing, in which case the cycle is repeated until all selected records have been played.

In the machine of the Smyth patent noted, the parts G to U, inclusive, are mounted upon a chassis or frame B which includes a mounting panel E, commonly referred to as a motor board, the same being secured directly to the casing or cabinet A. In order to obviate the undesirable transmission of vibration between the several operating parts and to the record reproducer means, the present invention contemplates the elimination of the chassis B and motor board E of the Smyth machine, and the provision of multi-part supporting means connected to the cabinet and interconnected with each other by resilient means having different periods of vibration so as to cause the vibrations which would normally be transmitted from one part to another to be damped out.

These means comprise a main mechanism supporting skeleton frame 11 secured to and suspended from the cabinet A by spring mountings, generally indicated by reference numeral 12, and an auxiliary frame 13 mounted upon the main frame 11 by means of resilient units 14 for supporting the record reproducer means H and the electric motor or turntable driving means O, the latter being suspended from the auxiliary frame 13 by spring means 15.

The main frame 11 preferably comprises longitudinally extending, front and rear L-shaped members 16 and 17, respectively, which support and have riveted thereto a pair of transversely extending, L-shaped end members 18 and a plate member 19. Resting upon, and riveted adjacent its ends to, the horizontal portions of the end members 18 is a longitudinally extending, U-shaped member 21. These several members 16, 17, 18, 19 and 21, which go to make up the skeleton main frame 11, have all of the phonograph mechanism heretofore referred to mounted thereon, with the exception of the electric motor or turntable rotating means O and the tone arm or reproducer means H, and provide the necessary clearance for those parts which extend both above and below the plane of the main frame 11 which they define. For example, the supporting bracket for the electric motor or cam driv-

ing means N depends from, and is bolted to, the U-shaped member 21 at 22.

The spring mountings 12 for securing the frame 11 to the cabinet A are four in number (Fig. 3), and are disposed, respectively, in co-operating relationship with the joined ends of the members 16 and 18, and the end portions of the rear member 17. At the former locations, the brackets forming a part of the mountings 12 are secured directly to the front wall of the cabinet, while in the two latter locations, they are secured to vertical struts or reinforcing members 23 forming a part of the cabinet structure. With particular reference to Fig. 4, it will be seen that each of the spring mountings 12 comprises a main bracket 24, a lower supporting bracket 25 and an upper guide bracket 26. The vertical arm of the main bracket 24 is secured in any suitable manner adjacent its upper end, with the guide bracket 26, to the front wall of the cabinet A or a strut 23, as at 27. The lower bracket 25 is likewise secured at 28. The main bracket 24 is provided with an inwardly extending, horizontal arm 29 which rests upon the lower bracket 25, and is provided with a vertical portion 31 which terminates below and in spaced relationship to the associated frame member 11 or 16, 18 in a horizontal flange 32. A cup-shaped retainer 33 is secured by welding, or in any other suitable manner, to the upper surface of the arm 29, and similar retainers 34 are secured in the same manner to the upper and lower surfaces of the associated main frame member, shown as the member 17 in Fig. 4, in vertical alignment with the retainer 33. A coil spring 35 is interposed between the retainer 33 and the lower retainer 34, and a similar spring 36 is positioned between the upper retainer 34 and a similar retainer 37 which is secured in any desired manner to the lower end of a sleeve 38 extending upwardly through a suitable guide aperture in the horizontal arm of the bracket 26.

The horizontal arm of the lower bracket 25, the arm 29 of the bracket 24, the horizontal portion of the associated main frame member (17 in Fig. 4), and the several retainers 33, 34 and 37 are each provided with suitable vertically aligned apertures through which, as well as though the springs 35 and 36 and sleeve 38, a bolt 39 extends. The head of the bolt 39 engages the upper end of the sleeve 38, and a nut 41 threaded on the lower end of the bolt engages the lower surface of the supporting bracket 25. Any desired degree of compression may thus be applied to the two springs 35, 36. The weight of the main frame 11 and the phonograph mechanism supported thereby is resiliently carried by the lower springs 35 of the several mountings 12, while the upper springs 36 yieldably resist upward movements of the frame relative to the machine casing. The vertically aligned apertures through which the bolt 39 passes, with the exception of the bore of the sleeve 38, are sufficiently larger than the outer diameter of the bolt to permit limited relative horizontal movements of the latter, the aperture in the guide bracket 26 likewise being larger than the outside diameter of the sleeve 38. The main frame 11 and the phonograph mechanism supported thereby are thus resiliently suspended for controlled floating motion relative to the outer cabinet A by the several mountings 12.

For the purpose of anchoring the main frame 11 and preventing movement of the same rela-

tive to the cabinet A during shipment of the phonograph, vertically aligned apertures 42 (Figs. 3 and 4) may be provided in the flanges 32 of the main brackets 24 and the associated frame members 17 and 18. A suitable bolt (not shown) may be passed through the associated apertures 42 and then tightened to draw the frame down into engagement with the flanges 32. While this same function could be accomplished by screwing up the nuts 41 on the bolts 39 to compress the springs 35, 36, the use of such auxiliary bolts enables proper adjustment of the bolts 39 at the factory to set the desired tension in the springs 35, 36, and eliminates the necessity of disturbing such accurate initial adjustment.

The auxiliary frame 13 (Figs. 2 and 3) comprises a flat plate, reinforced by having its sides flanged upwardly, which overlies the space between the plate member 19 and the right-hand end member 18. The resilient means 14 for mounting the auxiliary frame 13 on the main frame 11 are three in number, as best seen in Fig. 3, and are connected, respectively, to the rear member 17, the right-hand end member 18 and the plate member 19. Referring more particularly to Fig. 5, it will be seen that each of the auxiliary frame mounting means 14 comprises a lower resilient rubber block 43 interposed between the auxiliary frame and the main frame, and a similar rubber block 44 disposed above the auxiliary frame. A cup-shaped retaining member 45 is secured by welding, or the like, to the upper surface of the associated main frame member, shown as the member 18 in Fig. 5, and a similar retaining member 46 is welded to the underside of the auxiliary frame plate 13, the rubber block 43 being engaged therebetween. The several members 43 to 46 are each provided with centrally disposed apertures through which a sleeve 47 extends, and a washer 48 rests upon the upper end of the sleeve 47 and the upper surface of the rubber block 44. A bolt 49 extends downwardly through the sleeve 48 and a suitable aperture in the main frame member, and is provided at its lower end with a nut 51.

As shown in Fig. 5, tightening of the nut 51 against the main frame member 18 will thus rigidly interconnect the plate 48 and sleeve 47 therewith, the sleeve being of such length in relationship to the thickness of the associated members as to result in the two rubber blocks 43, 44 being maintained under a slight degree of compression. The auxiliary frame plate 13 has an aperture 52 through which the sleeve 47 extends and which, together with the aperture in the retainer 46, is of sufficiently greater diameter than the sleeve to permit relative movement between the two frames 11 and 13. Such movement, of course, is yieldably resisted by the resilient blocks 43 and 44.

The hollow, upright standard of the tone arm or reproducer means H is provided at its lower end (Figs. 3 and 5) with three radially extending bosses 53 which are secured to the auxiliary frame 13 by screws 54. The tone arm H is thus mounted in cushioned relationship to the turntable G by the resilient means 14, since the turntable is supported by the main frame 11, a suitable aperture being provided in the auxiliary frame plate 13 to accommodate the turntable shaft P.

Referring again to Figs. 2 and 3, the means

15 for suspending the electric motor or turntable rotating means O from the auxiliary frame 13 are three in number, each of which comprises a bolt 55, a washer 56 and a coil spring 57. The heads of the bolts 55 engage the washers 56 which span apertures 58 provided in the auxiliary frame plate 13, the apertures 58 having a greater diameter than the bolts 55. The lower ends of the bolts engage suitable tapped bosses provided on the supporting bracket of the turntable driving means O, and the springs 57 are interposed between these bosses and the auxiliary frame 13. The several turntable motor suspending means 15 extend downwardly through the space defined by the members 16, 19, 21 and the right-hand member 18 of the main frame 11.

From the foregoing description, it will be appreciated that the several different parts of the phonograph, and particularly the cam driving motor N and the mechanism operated thereby, 20 and the motor O for rotating the turntable, are so mounted in cushioned relationship to each other and the reproducer means H that vibrations caused by the operation thereof will not affect the tonal qualities of the record reproduction. Similarly, vibrations from outside sources, such as from accidental jarring of the cabinet, will not be transmitted to the record reproducer means. To assure these desired results by preventing the 25 building up, the amplification by synchronization or the superposing upon each other of different vibrations, the several different types of supporting units 12, 14 and 15 employed herein use resilient or vibratile members having such different 30 periods or frequencies that they co-act with each other to damp out and prevent transmission of the vibrations to the reproducer means.

It is thought that the invention and many of its attendant advantages will be understood from 35 the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

50 Mounting means for phonograph mechanism having an outer cabinet housing record carrying and selecting means, a rotatable turntable, record reproducer means, driving means for causing the positioning of a selected record on said turntable in operative association with said reproducer means, and means for rotating said turntable; comprising a frame member for supporting said reproducer means, means for mounting said turntable rotating means on said frame member including resilient members for cushioning relative movement therebetween, a second frame member 55 for supporting the other said mechanism, resilient members for mounting said first frame member on said second frame member, and resilient members interconnecting said second frame member and said cabinet, the different ones of 60 said resilient members having different periods of vibration to damp any vibrations emanating from said mechanism or from the exterior of said cabinet to minimize the transmission thereof to said record reproducer means.
